INVENTOR:

Edward J. Stahl
Geo. B. Pitts

ATTORNEY

UNITED STATES PATENT OFFICE

EDWARD J. STAHL, OF CLEVELAND, OHIO, ASSIGNOR TO THE BAKER-RAULANG COMPANY, OF CLEVELAND, OHIO, A CORPORATION OF OHIO

VEHICLE

Application filed June 27, 1929. Serial No. 374,236.

This invention relates to a vehicle in which the construction requires a plurality of manually operated devices, for example, for unlatching the door and raising and lowering a sash or other member. The invention may be adapted to a vehicle having a door and a sash movably mounted or associated therewith. In such adaptation, the invention is particularly adapted to a vehicle of the closed type, that shown by way of example in the accompanying drawings being termed a sedan.

The invention relates more particularly to the mechanisms or means for unlatching the door, whereby it may be opened and for raising and lowering the sash that may be associated therewith.

In all vehicles having a door or doors and a sliding sash associated with each door or either door, two separate operating means and manually operated devices therefor, respectively, have been provided at different positions on the door or other portion of the vehicle.

One object of the invention is to so combine these manually operated devices that a single mounting serves for both.

Another object of the invention is to so construct and mount the mechanism for unlatching the door and moving the sash associated therewith that many advantageous results are attained; for example, symmetry of the interior of the vehicle body and particularly the door panel is attained; the sash sill is free of weakened portions due to openings through it for operating devices or the like; the manually operated devices within the vehicle are disposed in the same location; the cutting of the trim for the interior of the door and any interior sheathing when required, is materially facilitated; and the ease of application of the sheathing and trim is greatly increased, both tending to effect economy in fabrication and final finish of the vehicle interior and the structural elements of the door may be more economically made and assembled.

Other objects of the invention will be apparent to those skilled in the art to which my invention relates from the following descrip-

tion taken in connection with the accompanying drawings, wherein

Fig. 1 is a fragmentary perspective view of the interior of a vehicle embodying my invention.

Fig. 2 is a fragmentary elevation of the door shown in Fig. 1.

Fig. 3 is a section on the line 3—3 of Fig. 2.

Fig. 4 is a fragmentary view, enlarged, of a portion of Fig. 3, but with certain of the parts broken away.

Figs. 5, 6, 6a and 7 are sections on the lines 5—5, 6—6, 6a—6a and 7—7, respectively of Figs. 2 and 3.

Fig. 8 is a fragmentary view similar to Fig. 2, but showing a different arrangement of the parts.

Fig. 9 is a section on the line 9—9 of Fig. 8.

Fig. 10 is a fragmentary elevation showing an embodiment of the invention but of slightly different construction.

Fig. 11 is a section on the line 11—11 of Fig. 10.

In the drawings, A indicates as an entirety a vehicle of any desired construction. As the invention is particularly useful in vehicles of the closed type, I have shown herein a vehicle ordinarily termed a sedan. In the illustration only one door B is shown but it will be understood that each door may be similarly constructed, as hereafter set forth. The frame work of the door B may be constructed in the usual manner to provide a lower portion b and an open frame b' forming a window opening closed by a sash C, which is slidable vertically in guides c. The guides c extend downwardly within the lower portion, whereby the opening may be uncovered or opened. The door B is hinged in the usual manner along one edge to a vertical post or stud of the body frame, for example, its front edge. Its opposite edge carries a latch casing 1 (see dotted lines in Fig. 2) supporting a latch 2, preferably of the sliding type, engaging a keeper (not shown), carried by the adjacent portion of the body frame. The casing 1 may enclose the usual spring for normally moving the latch 2 outwardly, a lock and release means for the latch and a shank for operating the latch.

from the usual handle exteriorly of the door; none of the parts just referred to being shown.

The latch 2 has connected to it a linkage 4 connecting it with a manually operated device 5, whereby the latter may be located at any desired distance from either edge of the door as well as at any desired position vertically relative to the casing 1.

10 The sash C is raised and lowered by a mechanism of any desired construction, but preferably a construction consisting of the following instrumentalities: 6 indicates a plate rigidly secured in the lower portion of the door B on the inner face of the door frame work 7 and provided with stud shafts for gears 8, 9, 10, constituting a gear train; one terminating gear (10) having fixed to it or its hub an arm 11 and the other terminating gear (8) meshing with a pinion 12 fixed to a shaft 13 (Fig. 4), to which is connected a manually operated device 14, so that when the latter is operated, the pinion 12 transmits power through the gear train 8, 9, 10, 20 to swing the arm 11 upwardly or downwardly. As the outer portion of the arm is operatively connected to the sash, such movement of the arm serves to adjust the latter. The weight of the sash may be counterbalanced in any desired manner, for example by a convolute spring 15 fixed at its inner end to the gear 10 and fixed at its outer end to the plate 6, as shown at 15a (Fig. 2).

30 The outer portion or end of the arm 11 carries on its outer face a roller 16, which rides or rolls on the side walls of a horizontally extending slot 17 formed in a plate 18, the latter being secured to the lower edge of the sash C. In Fig. 2, the sash C is shown in its uppermost position, but when the arm 11 is swung to the position x (see dotted lines in Fig. 2), the roller 16 acting on the plate 18 will move the sash downwardly, the slot 17 being elongated to permit traverse of the roller during such movement. The ratio between the pinion 12 and gear 10 is such that when the sash C is in either its extreme up or down position, the operating device 14 is disposed vertically and depending downwardly, as shown in Figs. 1, 2 and 3; and when the latch 2 is in its outward or normal position the operating device 5 is disposed vertically. In the form of construction shown in Figs. 1 to 7, inclusive, the device 5 depends downwardly, when in normal position, whereas in the form of construction shown in Figs. 8 and 9, the device 5 extends upwardly when in normal position.

40 19 indicates as an entirety a mounting for supporting the devices 5, 14, to permit them to rotate, each independently of the other, to retract the latch 2 or operate the sash. The mounting may be of sectional form, but it preferably consists of castings comprising a main section 20 having a central section 21

and a lower or depending section 22. The upper portion of the main section 20 is extended laterally to form a flange 20a which engages the horizontal sill of the window opening, being secured thereto by screws 23. 70

The flange 20a is shaped in cross section to fit the cross-sectional shape of the sill as shown in Fig. 3. As shown at 20b, the section 20a is provided along its upper portion

75 with an upstanding wall which forms a finger hold adapted to be engaged by the finger tips as a means of closing the door, although, when desired, either one of the devices 5, 14, may serve as a pull-to device. The central section 21 is connected at its upper

end to the section 20. For this latter purpose, the section 20 is shaped to provide a laterally extending wall 21a so that the section 21 will be in a plane inwardly of the section 20. At its opposite inner sides and in

80 spaced relation to the lower end of the section 20, the section 21 has inwardly extending flanges or lugs 21b (see Figs. 2 and 6) for engaging the inner face of the lower or depending section 22, the members 21b serving

85 to position the section 22 in a plane outwardly of the section 21 and preferably substantially in the plane of the section 20. By arranging the section 21 in a plane inwardly

89 of the sections 20 and 22, a bearing is pro- 90 vided for the shaft which carries the device

5 and a wall is provided between the devices 5, 14, so that in operating the latter the hand or fingers of the person are protected against

95 becoming caught in the device 5. By the pro- 100 vision of the section 22, greater rigidity of the mounting results and the section 21 is supported to take the stresses incident to the

105 rotation of the devices 5, 14. The section 22 is secured to the door frame by countersunk

110 screws 24 (see Fig. 3), these screws being disposed along a vertical line cutting the

115 axis of the shaft 13 so that the device 5 will hide them when in normal position.

25 indicates a tubular member having at 110 its outer end a flange 25a which is secured to the plate 6. The inner end of the tubular member is fitted in an opening 26 formed in the section 21. The hub 5a of the device 5 is rotatable on the tubular member. The

115 hub 5a is provided on its side remote from the device 5 with an arm 5b to which the inner end of the linkage 4 is connected in

any desired manner, preferably by a nut and bolt 28. 29 indicates a spacing collar

120 between the flanges 25a and hub 5a serving, in part, to prevent movement of the latter endwise of the tubular member 25. The inner end portion of the tubular member 25 is

125 interiorly threaded to receive the threaded portion of a collar 30 which has a flange 30a engaging the exposed face of the section 21.

The hub 5a is held in place on the tubular member by the member 21 and is held in

130 proper spaced relation from the flange 25a by

the collar 29. The shaft for the pinion 12 extends through the tubular member 25 and is fitted within an opening 31 formed in the hub 14a of the device 14, being keyed thereto in any desired manner, as by serrations as shown. The hub 14a is reduced, as shown at 14b, such reduced portion rotatably fitting the collar 30 and the resulting shoulder bearing against the outer end of the collar.

10 To lock the hub 14a against outward movement, I form on the outer portion of the collar 30 an annular recess to provide a shoulder 32 and I mount on the outer portion of the hub 14a a flat ring or washer 33 held in place 15 by a split spring 34, which rotatably fits an annular recess formed in the hub 14a. The spring 34 is telescoped over the free end of the hub 14a and sprung into its recess, but as a portion of the spring lies outside of its recess such portion forms an abutment or lock 20 to hold the ring 33 in position and thus locks the hub and collar together.

Instead of providing the section 20 with one or a pair of inwardly extending walls, 25 such walls may be multiplied to give an ornamental effect, so that the central portion of the section forming a support for the tubular member 25 is in one plane and side portions or wings 21c are in another plane and 30 the section 20 is in a different plane outwardly; also the sections 20, 21 and 22 may have different widths progressively for ornamental reasons.

In the construction of a vehicle having a 35 single mounting for the manually operated devices for the door latch and window, the door frame is required to have but one operating space D to accommodate the linkage 4, tubular member 25, hub 5a and arm 5b. It 40 will also be noted that in such a construction, the sheet material E (if provided) and fabric E' forming the interior trim need have but one opening formed in it to accommodate the tubular member 25 and hub 5a. The trim is 45 therefore much simplified which enables it to be more readily cut and also fitted to the interior of the vehicle. Since my construction requires but a single opening in each of the trimming materials, changes in the dimensions 50 of such materials can be readily effected.

When it is desired to mount the latch operating device to extend upwardly but in line with the sash operating device 14, when in normal position, the section 21' of the mounting is connected at its lower end to the section 22' and the opposite portion at its upper end is connected to the section 20', this form of construction being shown in Figs. 8 and 9. 55 In this form of construction the upper portion of the section 21' is spaced from the section 20' to accommodate the device 5' so that it may swing to either side of the vertical or its normal position (Fig. 8). In this arrangement the linkage 4 is preferably con-

nected to an arm 5b' extending from the side of the hub 5a' remote from the device 5'.

Figs. 10 and 11 show a slightly different embodiment of the invention in which the operating devices rotate on or swing about separate axes. For this purpose I provide on the section 22a a shoulder pin 35 and pivot the latch operating device 5a thereon. The pin 35 has a reduced portion extending through an opening formed in the section 22a, a nut 36 being threaded on its outer end to secure the shaft thereto. The outer end of the shaft 35 is preferably headed to hold the device 5a in position. As shown in Fig. 11, the door frame is cut away at b² to accommodate the nut 36 and shaft end.

In my form of construction both operating devices 5, 14, are always the same distance from either seat. They are preferably located centrally of the door to secure symmetry. In a vehicle having the door between the front and rear seats, both devices may, when desired, be mounted equal distances from both seats to insure equal access by the person occupying either thereof.

My construction is advantageous as it insures symmetry in the appearance of the vehicle interior; it also simplifies fabrication and insures greater economy, as already set forth. It also leaves a larger unobstructed surface on the door panel which may be used for other purposes, such as the provision of extra pockets. In the use of the term sash herein I do not wish to be limited to a window having a frame as it is customary to provide windows consisting of sections of glass without sash frames therefor, except along their lower edges.

From the foregoing description it will be noted that I provide a single, unitary mounting for both operating devices and that the latter rotate or swing about axes disposed in the same plane, preferably the same vertical plane. In the preferred form of construction, these devices rotate or swing about a common axis. In either form of construction, the devices, when in normal position, are disposed one in front of the other and in a common plane.

To those skilled in the art to which my invention relates, many changes in construction and widely differing embodiments and applications of the invention will suggest themselves without departing from the spirit and scope thereof. My disclosures and the description herein are purely illustrative and are not intended to be in any sense limiting.

What I claim is:

1. In an operating mechanism adapted to be mounted on a vehicle panel having a latch member and a movable member, the combination of a mounting on the interior side of the panel, said mounting comprising upper and lower sections in vertically spaced relation and an intermediate section, an operat-

- ing device pivoted in the intermediate section and disposed inwardly thereof, an operating device pivoted on an axis on a horizontal line co-incident with the axis of said first mentioned device, and operating means between each said device and one of said members.
2. In an operating mechanism adapted to be mounted on a vehicle panel having a latch member and a movable member, the combination of a pair of operating devices pivoted on said panel on a common axis, and operating means between each said device and one of said members.
3. In an operating mechanism adapted to be mounted on a vehicle panel having a latch member and a movable member, the combination of a mounting comprising a plate and a support adapted to be carried by the panel, a tubular member supported by said plate and said support, an operating device having a hub rotatably fitting within said tubular member, an operating device having a hub rotatably fitting the exterior wall of said tubular member, and operating means between each hub and one of said first mentioned members.
4. In an operating mechanism adapted to be mounted on a vehicle panel having a latch member and a movable member, the combination of a mounting comprising a plate and a support adapted to be carried by the panel, said support comprising upper and lower sections secured to the inner side of the panel and an intermediate section, a tubular member supported by said plate and said intermediate section, an operating device having a hub rotatably fitting within said tubular member, an operating device having a hub rotatably fitting the exterior wall of said tubular member, and operating means between each hub and one of said first mentioned members.
5. In an operating mechanism adapted to be mounted on a vehicle panel having a latch member and a movable member, the combination of a mounting comprising a plate and a support on the panel, said support comprising upper and lower sections secured to the inner side of the panel and an intermediate section, a tubular member supported by said plate and said intermediate section, an operating device having a hub rotatably fitting within said tubular member, an operating device having a hub rotatably fitting the exterior wall of said tubular member, and operating means between each hub and one of said first mentioned members, the intermediate wall being extended and disposed between said operating devices.
6. In an operating mechanism adapted to be mounted on a vehicle panel having a latch member and a movable member, the combination of a pair of spaced plates adapted to be secured to the inner surface of the panel, operating handles each having a hub adapted to be connected to one of said members, and means for supporting said hubs on said plates to swing about a common axis.
7. In an operating mechanism adapted to be mounted on a vehicle panel having a latch member and a movable member, the combination of spaced plates adapted to be secured to the panel, a tubular support supported by said plates, an operating handle having a hub rotatably mounted within said tubular support and adapted to be operatively connected to one of said members, and an operating handle having a hub rotatably fitting the exterior wall of said support and adapted to be operatively connected to the other member.
8. In an operating mechanism adapted to be mounted on a vehicle panel having a latch member and a movable member, the combination of spaced plates adapted to be secured to the panel, a tubular support supported by said plates, an operating handle having a hub rotatably mounted within the tubular support and adapted to be operatively connected to one of said members, and an operating handle having a hub rotatably fitting the exterior wall of said support and adapted to be operatively connected to the other member, one of said plates having a portion extending between said handles to form a guard.
9. In an operating mechanism adapted to be mounted on a vehicle panel having a latch member and a movable member, the combination of spaced plates adapted to be secured to the panel, a tubular support supported by said plates, an operating handle having a hub rotatably mounted within the tubular support and adapted to be operatively connected to one of said members, an operating handle having a hub rotatably fitting the exterior wall of said support and adapted to be operatively connected to the other member, said handles being movable in different vertical planes, and a guard disposed in a plane between said handles.
10. In an operating mechanism adapted to be mounted on a vehicle panel having a latch and a movable member, the combination of a mounting adapted to be fixed to the interior surface of the panel, and comprising upper and lower related sections and an intermediate section connected to one of first mentioned sections and disposed in spaced parallel relation to the other of said sections, and a pair of operating devices revolvably supported on said mounting, one connected to and adapted to operate the latch and the other connected to and adapted to operate the movable member, one of said devices being movable in a plane in front of said intermediate section and the other device being movable in a plane behind said intermediate section.
11. In an operating mechanism adapted to

be mounted on a vehicle panel having a latch and a movable member, the combination of a mounting adapted to be fixed to the interior surface of the panel, and comprising upper and lower related sections and an intermediate section connected to one of first mentioned sections and disposed in spaced parallel relation to the other of said sections, and a pair of operating devices supported on said mounting to revolve about a common axis, one connected to and adapted to operate the latch and the other connected to and adapted to operate the movable member, one of said devices being movable in a plane in front of said intermediate section and the other device being movable in a plane behind said intermediate section.

12. In a dual operating mechanism adapted to be mounted on the door of a vehicle having a latch member and a movable member, the combination of inner and outer spaced plates adapted to be secured to the inner and outer surfaces of the door, a tubular support supported at one end by said outer plate and extending into and supported by the walls of an opening formed in the other plate, an operating handle having a hub rotatably mounted on the exterior wall of said support between said plates, said hub having a connection with one of said members, and an operating handle having a hub rotatably mounted within said support on the opposite side of said inner plate from said first mentioned handle, said hub having connection with the other of said members, said inner plate being extended to serve as a guard device between said handles.

In testimony whereof I have hereunto affixed my signature.

40 EDWARD J. STAHL.
